His Attorney.

UNITED STATES PATENT OFFICE.

EDWARD A. WAGNER, OF PITTSFIELD, MASSACHUSETTS, ASSIGNOR TO GENERAL ELECTRIC COMPANY, A CORPORATION OF NEW YORK.

ELECTRICAL-APPARATUS CORE.

Application filed April 2, 1927. Serial No. 180,586.

My invention relates to magnetic cores of electrical apparatus. To be efficient, the magnetic core of a piece of electrical apparatus such as a transformer must be of laminated construction and the laminations more or less well insulated from each other. This construction prevents excessive eddy currents with high losses in the core. The laminations are commonly secured together in a compact stack by means of bolts or rivets extending through suitable openings in the laminations, these bolts or rivets being also insulated to prevent short circuiting the laminations. The usual bolt or rivet is circular in cross section and, with its insulation, obviously occupies an appreciable part of the cross section of the part of the core in which it is located. This increases the magnetic reluctance of the core and makes necessary a larger core than would otherwise be required. Predetermination of the magnetic characteristics of the core is also difficult if a considerable portion of the cross section of the parts of the core is taken up by bolts or rivets. This proportion is greater in small than in large cores, so that the objection to the presence of the bolts or rivets is greatest in the small cores. The general object of the invention is to provide a core construction in which the disadvantages inherent in the round bolts and rivets heretofore used for securing the laminations together are reduced but without any sacrifice of strength.

The invention will be better understood from the following description taken in connection with the accompanying drawing in which Fig. 1 is a perspective view of a transformer with its core laminations secured together in accordance with the invention and Fig. 2 is a view of the same transformer looking toward one face of the core, a small part of one of the core yokes being broken away on the line 2 of Fig. 1.

Like reference characters indicate similar parts in both figures of the drawing.

The invention will be described in connection with the transformer shown in the drawing. This transformer comprises a magnetic core 10 having a winding leg 11, yokes 12, two outer legs 13 joining the outer ends of the yokes, and windings 14 surrounding the winding leg 11. The core 10 is formed of a stack of magnetic laminations of suitable material such as silicon steel, these laminations being secured together in a tightly compressed unit by a plurality of rivets 15 distributed at suitable intervals along the parts of the core. The round rivets and bolts heretofore used for this purpose have been selected in as small sizes as was consistent with the necessary strength in order to take up as little as possible of the cross section of the core parts. In accordance with the present invention, the dimension of each rivet and bolt is still further reduced in the direction across the part of the core in which it is located or across the adjacent path of the magnetic flux and, in order that it may still have the necessary strength, the dimension along this part of the core or parallel with the path of the flux is increased. This increase in the dimension of the rivet or bolt in the direction of the path of the magnetic flux has little or no effect on the reluctance of the magnetic circuit of the core and may be as great as necessary to provide a rivet or bolt with proper cross section and strength. Each rivet or bolt is surrounded by a thin layer of insulation to avoid short circuiting the core laminations as shown in Fig. 2 where a small section of the upper laminations is broken away and the cross sectional view of a rivet is shown with its layer of insulation indicated by a heavy line.

While a particular form of electrical apparatus has been described and illustrated with its core laminations secured together in accordance with the invention, it will be apparent that various changes may be made within the scope of the invention as defined in the appended claims.

What I claim as new and desire to secure by Letters Patent of the United States, is:

- An electrical apparatus core comprising a stack of magnetic laminations, and means extending through openings in said laminations for securing them together, the cross sectional dimensions of said securing means

across the core parts through which they extend being less than their cross sectional dimensions along said core parts.

2. An electrical apparatus core comprising a stack of magnetic laminations, and means extending through openings in said laminations for securing them together, the cross

sectional dimension of each of said securing means across the adjacent path of the magnetic flux being less than its cross sectional dimension along said flux path. 10

In witness whereof, I have hereunto set my hand this 31st day of March, 1927.

EDWARD A. WAGNER.
